UNITED STATES PATENT OFFICE.

LOUIS SIMON AND ROBERT A. F. DE BANRET, OF CHICAGO, ILLINOIS.

BRIDGE-GATE.

SPECIFICATION forming part of Letters Patent No. 781,373, dated January 31, 1905.

Application filed February 15, 1904. Renewed December 23, 1904. Serial No. 238,150.

To all whom it may concern:

Be it known that we, LOUIS SIMON and ROBERT A. F. DE BANRET, citizens of the United States, residing at Chicago, in the county of 5 Cook and State of Illinois, have invented certain new and useful Improvements in Bridge-Gates; and we do hereby declare the following to be a full, clear, and exact description of the invention, such as will enable others 10 skilled in the art to which it appertains to make and use the same.

Our invention relates to a novel construction in a bridge-gate, the object being to provide a gate for swinging bridges which is operated by the movements of the bridge to close 15 the approach when the bridge is opened, and vice versa; and it consists in the features of construction and combinations of parts hereinafter fully described and claimed.

20 In the accompanying drawings, illustrating our invention, Figure 1 is a horizontal section showing the end portion of a swinging bridge and approach thereto provided with an automatic gate constructed in accordance with 25 our invention. Fig. 2 is a transverse section on the line 2 of Fig. 1, showing our device partly in section.

Our said device is designed to operate automatically with great ease, so that the strains 30 on the bridge-operating mechanism and on the structure itself in opening and closing the gate shall be reduced to a minimum.

It is also our object to provide gates which are ornamental in appearance and which efficiently bar the approach, so that pedestrians, 35 horses, and vehicles of all kinds cannot inadvertently plunge from the edge of the approach when the bridge is open.

To this and other ends our device consists 40 of a frame A, comprising the standards B and D, mounted adjacent the edge of the approach and joined at their upper ends by means of an ornamental cross-beam E. The post C is mounted in the plane of said standards B and 45 D midway between same and is adapted to receive the lower end of the vertical sliding bar G, the upper end of which passes through a bearing on said cross-beam E and is provided with the antifriction-roller H, which is 50 adapted to be engaged by a cam I, mounted

on the free end of the bridge J. Pivottally mounted at their ends on said post C are two swinging bars K, which are connected, by means of links L, with the block F, which is adjustably mounted on said rod G, so that as 55 the latter is raised said links will draw up said bars. Said bars K are provided at their inner ends with segmental teeth M, which mesh with a rack-bar N, movable in a well formed in said center post C and which carries a counterweight O at its lower end, which is adapted to partially counterbalance said bars K and the operating mechanism connected therewith. To each of said standards B and D we secure projections P, in the upper ends of 65 which are recesses in which the bars are adapted to be received when they are lowered to support same horizontally in proper position to shut off the approach. Said bars are of a length sufficient to project over the foot-walks 70 Q of the approach, so as to prevent accidental overstepping by pedestrians. The said cam I is provided with a curved upper edge so arranged as to attain its greatest height at its middle portion, so that when the bridge is 75 closed the said roller H and bar G are held thereby at the upper limit of their movement. Said cam I is concentric with the pivot of the bridge for obvious reasons.

The height of the cross-beam E above the 80 bridge-approach may be changed and varied to suit various conditions and may obviously be changed or varied in form to enable guides for car-trolleys to be mounted thereon, and the relative positions of the standards and the 85 number and relative spacing of same may obviously also be changed and varied without departing from the spirit of our invention.

We claim as our invention—

1. The combination with a swinging bridge 90 and a cam carried thereby, of a frame mounted on the approach, swinging bars pivotally mounted thereon, a vertically-movable block mounted on said frame, an antifriction-roller connected therewith and adapted to be engaged by said cam to raise and lower said block, and links connecting said blocks with said bars to transmit motion thereto in accordance with the movements of said bridge. 95
2. The combination with a swinging bridge, 100

of a cam mounted on the upper end thereof, a frame mounted on the bridge-approach adjacent the edge, a vertical guide on said frame, a block movable thereon, an antifriction-roller 5 connected with said block and extending into the path of said cam to be raised and lowered thereby, bars pivotally mounted on said guides, links connecting said bars with said block, segmental gears concentric with the pivots of 10 said bars, a double rack - bar meshing with said gears and vertically movable in a recess provided therefor, and a counterweight carried by said rack-bar and adapted to partially counterbalance said bars and parts connected 15 therewith.

3. The combination with a swinging bridge, of a cam mounted on the upper end thereof, a frame mounted on the bridge-approach adjacent the edge, a vertical guide on said frame, 20 a block movable thereon, an antifriction-roller connected with said block and extending into the path of said cam to be raised and lowered thereby, bars pivotally mounted on said guide, links connecting said bars with said block, 25 segmental gears concentric with the pivots of said bars, a double rack - bar meshing with said gears and vertically movable in a recess

provided therefor, a counterweight connected with said rack and adapted to partially counterbalance said bars and operating mechanism 30 connected therewith, and stops mounted on said frame and adapted to receive said bars when lowered to support same in proper relative position to close said bridge - approach.

4. The combination with a swinging bridge, 35 and a cam carried thereby, of a standard mounted in the middle portion of the bridge-approach, a vertically-movable block mounted on said standard, an antifriction-roller connected therewith and adapted to be engaged 40 by said cam to raise and lower said block, swinging bars pivotally mounted on said standards, links connecting said bars with said block, and a counterweight interposed in said mechanism to partially counterbalance the 45 weight thereof to relieve said cam of strain.

In testimony whereof we affix our signatures in presence of two witnesses.

LOUIS SIMON.

ROBERT A. F. DE BANRET.
